UNITED STATES PATENT OFFICE.

PETER C. REILLY, OF INDIANAPOLIS, INDIANA.

METHOD OF DISTILLING COAL-TAR OR COAL-TAR PITCH AND PRODUCTS DERIVED THEREFROM.

1,230,782.

Specification of Letters Patent. Patented June 19, 1917.

Application filed March 28, 1914. Serial No. 827,965.

To all whom it may concern:

Be it known that I, PETER C. REILLY, a citizen of the United States, residing at Indianapolis, in the county of Marion and 5 State of Indiana, have invented certain new and useful Improvements in Methods of Distilling Coal-Tar or Coal-Tar Pitch and Products Derived Therefrom, of which the following is a specification.

10 My present invention pertains to an improved method of distilling coal tar or coal tar pitch, and to the products produced thereby.

15 The method may be successfully carried out by the use of a still such as is shown in the annexed drawings, wherein:

Figure 1 is a longitudinal vertical sectional elevation of the still and its setting; and

20 Fig. 2 a front elevation thereof.

One object of the invention is to so treat coal tar that the entire volatile portion or portions thereof will be carried off, producing certain substances or products not 25 heretofore commercially known, and likewise producing a coke, sponge-like in appearance which, along with the products (distillates), has a commercial value.

Various attempts have heretofore been 30 made to completely distil coal tar and coal tar pitch (see Lunge, "Coal Tar and Ammonia", 4th edition, 1909, pp. 454, *et seq.*) but so far as I am aware such attempts have not been successful, and apparently for the

35 reason that one or another part of the still has been allowed to stay cool or relatively so, with the resultant effect that the vaporized matter is condensed and drops back into the mass below, whereas in carrying

40 out my process the still in its entirety is kept at a substantially even temperature. Various forms of stills have likewise been suggested and used, such as brick, cast iron, and wrought iron stills; the first two men-

45 tioned are ineffective for well recognized reasons, and as stated by Lunge, (p. 323) "Only one material is suitable for tar stills, viz., wrought iron". Such wrought iron stills have been successfully used in the

50 "first distillation of coal tar", but where their use has been attempted for the distillation of coal tar pitch it has failed. Thus, in speaking of the distillation of pitch for coke, Lunge, page 454, makes the following 55 observation: "The apparently simplest plan,

that of carrying on the process in the tar-still itself to the stage of coke, is not feasible. We have seen, page 323, that cast iron is not well adapted for tar distilling, and wrought iron would be burnt away too quickly". * * * "The brick pitch-ovens, which were sometimes formerly employed will be but briefly mentioned here, as they have not proved practically successful."

In carrying out my process I employ a 65 still so mounted or housed that it is subjected, in its entirety, to a substantially even temperature throughout. In other words, the products of combustion which emanate from the furnace pass entirely around the 70 still, and both ends thereof, so that the still, as just noted, is subjected to an even temperature, and the condensation of the distillates within the still is prevented. Apparently, the use of wrought iron stills for the 75 purpose of completely distilling coal tar so as to drive off all of the vaporizable elements thereof, and to leave nothing but coke, has not been successful, for the reason that the heat has been applied to the lower 80 portion only of the still. As a consequence of such operation the products which are driven off in the lower portion of the still come in contact with the relatively cool upper portion thereof, and are thereby con- 85 sealed and drop back into the lower portion of the still, commingling with the charge therein.

In the drawings, I have disclosed a simple form of still and housing or mounting, 90 wherein 1 indicates the still proper, shown in the form of a cylindrical chamber and provided with a manhole 2 in the upper portion thereof, and a manhole 3 opening into the lower portion of the still through one 95 end or head thereof. A pipe 4 extends from the upper portion of the still and carries off the products which are produced, owing to the action of the heat, as is well understood. The fire chamber is indicated by 5, 100 and as will be noted is preferably located adjacent to the front wall 6 of the mounting and over said fire chamber I provide a fire arch 7, the products of combustion passing outwardly through a flue or opening 8, 105 formed beneath said arch and the inner wall 9 of the fire chamber. The outlet for the products of combustion is indicated by 10, and as will be noted, it is located in the rear wall of the mounting, at the lower 110

portion thereof, said opening discharging into a lateral flue 11, which flue extends to a stack, which is not shown in the drawings. In practice, a battery of stills is employed, 5 the housing or mountings all being alike and the lateral flue 11 serving all of the stills. A fire wall 12 guards the outlet 10, said wall extending well upwardly toward the lower portion of the still so that the products of 10 combustion cannot pass directly from the opening 8 to the outlet 10. Naturally, the products of combustion being the hottest as they emanate from the opening 8, will rise and come into contact with the still. As 15 noted, the still is spaced away from the wall of the mounting throughout, and is supported by brackets 13, riveted to the sides of the still and resting in the brick-work or the walls of the still housing. Thus 20 it will be seen that except for the relatively small area of contact of the manholes 2 and 3, the pipe 4, and the brackets 13, the still is suspended in space in the upper portion of the mounting and is subjected on all 25 sides to the products of combustion passing from the furnace.

With a still thus constructed and mounted, I have been able to completely distil coal tar upon a large scale commercially. 30 Thus, with a 5000 gallon still, the operation may be concluded in anywhere from eighteen to thirty six hours, dependent upon the nature of the coal tar employed.

During the first portion of the distillation 35 of the coal tar (assuming that coal tar and not coal tar pitch be placed in the still), the operation is as usual; that is to say, the water followed by the light oils (phenol group) first passes over. The heavier oils 40 then pass over, such oils containing naphthalene and the beginning of the anthracene. These are followed by the anthracene. Such products, of course, are well known, and commercially derived from coal tar. From this 45 point on, however, the method and operation are different from those heretofore known. Ordinarily, where the heat is applied merely to the under portion of the still, such portion acquires at first a semi- 50 solid deposit and finally a solid deposit, practically dry, and to a large degree impervious to heat, so that the liquid mass lying above such coating or deposit cannot be reached by the heat applied to the bottom 55 of the still. The residue or matter lying above such layer is still undistilled and contains a large quantity of volatile matter of a high specific gravity, which I have discovered contains valuable material, particularly for use as preserving compounds for 60 the treatment of wood, with the view of waterproofing the same.

With a still such as herein set forth I am 65 enabled to cause the heat to reach the mass from all directions and to produce a final

or ultimate distillation of all the volatile portions, leaving a perfectly dry and easily-removable coke.

After the anthracene has passed over, the heat which is applied to the still is gradually raised to a temperature of substantially 70 1000° F. At first, at a temperature of from 700° to 800° F. there passes over an orange-colored mass which is waxy at 70° F., and this is followed, when the temperature is 75 raised to approximately 1000° F., by a substance which, when cool, is hard and brittle at 70° F. The latter product, when shaved with a knife, takes a flaky form, 80 presenting a brilliant garnet color. The surface of the body of material, when so cut, likewise presents a relatively brilliant face, and a similar color. This material has a specific gravity of not less than 1.22 85 taken at 20° C. The other, waxy material, runs all the way from the specific gravity of anthracene, to wit, 1.147, up to 1.22, 90 about which point the color changes from an orange to a garnet color, in the harder material. Both of these products are non-volatile at ordinary temperatures, and by 95 reason of such characteristic are of great value for preservative and other purposes. Such products, so far as I am aware, are not found in any appreciable quantity as 100 a distillate under any of the processes of distillation heretofore known, and are formed by the cracking or decomposition of the material by the heat which I am enabled to apply to the mass as a whole.

If coal tar pitch be placed in the still, the first products passing over will, of course, be the heavier oils. Beginning with the heavier oils, the products and residue from 105 coal tar pitch are the same as those from coal tar, and the process of distillation is the same as above described.

The coke which remains after the distillation is fully completed, is dry and sponge-like in appearance, and is easily removable 110 from the still. The coke may be further identified by the fact that it presents upon fracture a steel-gray surface upon the lines of fracture, with a brilliant or glossy surface upon the walls of the depressions, 115 pockets or recesses which appear therein. It is also amorphous, non-crystalline, and sponge-like in appearance. Furthermore, when burned, it leaves a residue of approximately two per cent., composed of non-combustible matter and mineral ash.

The final heavy products above referred to are produced by the decomposition of the material and the molecular re-formation thereof after the anthracene has ceased to 125 pass over during the distilling operation.

The use of a still as herein set forth, not only produces the new materials just specified, which have a high commercial value, but it is also advantageous in the first dis- 130

tillation of coal tar to produce the ordinary products therefrom, in that the heat is applied to the entire still and the distillation is effected with rapidity and economy.

5 No claim is herein made to the still by means of which the method above described may be carried out, and the products set forth are produced, the same being reserved for a copending application, filed on about 10 the 28th day of March 1914, Serial No. 827,967.

Having now described my invention, what I claim is:

1. The process of distilling coal tar, which 15 consists in placing a charge thereof in a still; subjecting the entire exterior surface of the still to a substantially even temperature; and carrying the temperature to such a high degree as to drive off all the volatile products 20 from the charge, leaving as a residue within the still a dry coke.

2. The process of distilling coal tar, which consists in placing a charge thereof in a still; subjecting the entire exterior surface of the 25 still to a substantially even temperature; and gradually increasing the temperature of the still over its entire surface to such a degree as that the final product driven off will have a specific gravity of not less than 1.22 at 30 20° C.

3. The process of distilling coal tar, which 35 consists in subjecting a charge thereof in a still to an even or like temperature over its entire surface, thereby driving off the volatile products from the coal tar; and finally, after the passage of the anthracene oils from the still, carrying the temperature of the still to approximately 1000° F., whereby there 40 will first be carried over an orange-colored product waxy at 70° F., and afterward a hard, garnet-colored product, brittle at 70° F.

4. The method of producing a dry coke 45 from coal tar pitch and likewise producing an orange-colored mass waxy at 70° F. and a hard, garnet-colored mass brittle at 70° F., which consists in subjecting the coal tar or coal tar pitch to a temperature of substan-

tially 1000° F. in a still subjected to a substantially even temperature over its entire 50 surface.

5. As a new article of manufacture, an orange-colored mass waxy at 70° F. and having a specific gravity of from 1.147 to 1.22, and produced from coal tar or coal tar pitch 55 subjected to a temperature of substantially from 700° to 800° F.

6. As a new article of manufacture, a hard garnet-colored product brittle at 70° F. and having a specific gravity of not less than 60 1.22, produced as a final product of distillation passing from coal tar or coal tar pitch when subjected to a temperature of approximately 1000° F.

7. As a new article of manufacture, coke 65 produced as the result of the complete distillation of coal-tar, said coke being characterized by the fact that it is sponge-like in appearance, amorphous, and non-crystalline, is dry, and when burned leaves a residue 70 approximating two per cent. composed of non-combustible matter and mineral ash.

8. As a new article of manufacture, coke 75 produced by the complete distillation of coal-tar, said coke being characterized by being dry and sponge-like in appearance, amorphous, non-crystalline, and presenting when fractured a steel-gray surface upon the lines of fracture, with a brilliant or glossy surface upon the walls of the depressions, 80 pockets or recesses appearing therein.

9. That process of completely distilling coal-tar, which consists in placing a charge 85 of the material in a still; bathing the entire still in a heated atmosphere; and raising the temperature of the same to such a degree as to fractionate and drive off all volatile products and leaving as a residue within the still, upon completion of the operation, a dry coke.

In testimony whereof I have signed my 90 name to this specification in the presence of two subscribing witnesses.
